S. E. CARNEY

SPLICE

Filed March 10, 1927

UNITED STATES PATENT OFFICE.

SAMUEL EVERETT CARNEY, OF WICK, WEST VIRGINIA, ASSIGNOR OF ONE-HALF TO JOHN M. ROAN, OF CAMBRIDGE, OHIO.

SPLICING.

Application filed March 10, 1927. Serial No. 174,363.

This invention relates to splices and more particularly to a splice between flexible cable and rope and a means for protecting the same.

5 An important object of the invention is to provide a device of this character which will protect the rope at the splice against the fraying ordinarily occurring due to contact of the rope with the wall of a bore 10 through which it is passing.

In oil well drilling apparatus, splices of this character are very often employed and as is well known to those familiar with the art, the bore of an oil well is usually very 15 crooked, so that there is a natural tendency of the splice to come into contact with the casing. This tendency is increased by the tendency of the rope and cable to "whip" in operation. As the formation of the splice 20 causes the effective diameter of the rope to increase at the splice, this part, which is naturally weak, is subjected to an unusual wearing strain, with the result that the rope will break at the splice. Accordingly, an 25 important object of the invention is to produce a protection for the rope at the splice, preventing this contact.

A further object of the invention is to produce a protecting device which will not 30 in any way interfere with the passage of a rope knife over the splice.

These and other objects I attain by the construction shown in the accompanying drawings, wherein for the purpose of illustration is shown a preferred embodiment of 35 my invention and wherein:—

Figure 1 is a side elevation partially in section of a rope and cable splice embodying protecting devices constructed in accordance with my invention:

Figure 2 is an enlarged vertical sectional view therethrough;

Figure 3 is a detail fragmentary side elevation of the cable showing the manner in 45 which some of the strands are cut away to reduce the size thereof.

Referring now more particularly to the drawings, a splice between cable and rope is usually formed by separating the strands 50 S of the rope and laying the cable C therein as a core. In order that the rope strands, when rewound about this core, may not be formed with too abrupt a shoulder at a point intermediate the ends of the splice, a number of the strands S' of the cable are

cut away, leaving only two or three strands thereof, which extend to the lower end of the splice. It will be obvious that when the rope strands are wound about a cable reduced in this manner, the diameter of the 60 rope in the complete splice will increase at two points 10 and 11. The free ends of the strands of the rope are usually thinned before wrapping the same about the cable, with the result that the upper end of the splice 65 tapers, as more clearly indicated at 12.

In accordance with my invention, I provide metallic sleeves 13 and 14, fitting the rope closely at the enlargements 10 and 11 and secure these sleeves in position upon the 70 rope by securing elements 15 extending through the metal sleeve and into the strands of the rope.

Upon the tapered upper end 12, I secure a conical sleeve 16, the upper end of which 75 has an internal diameter equal to the diameter of the cable C and the lower end of which has an internal diameter equal to the diameter of the rope at the lower end of the conical portion of the splice. This sleeve 80 may be slid upon the cable C before the splice is formed and upon completion of the splice is moved downwardly over the tapered portion and secured by securing elements 17 extending into the strands of the rope. 85

A structure of the above character, in addition to protecting the rope against external wear, serves the additional function of preventing the loose ends of the cable strands from cutting the strands of the rope. In the 90 ordinary construction of such a splice, these loose ends must be seized, as otherwise the loose ends of the strands, when the rope tends to bend at the point where the strands are located, will cut the fiber of the rope 95 strands S and weaken the same to a point where the rope will tend to part, even though it is not externally frayed to a dangerous point. Breakage of this character is more dangerous than that resulting from external fraying, in that being invisible, the breakage is unexpected and proper precautions may not have been taken, so that damage may result to those in attendance upon the drilling. With the structure which I employ, the sleeves 13 and 14 stiffen the sections of the rope within which the strand ends are located, preventing flexing thereof and accordingly preventing cutting.

Since the construction hereinbefore set 110

forth is capable of a certain range of change and modification without materially departing from the spirit of the invention, I do not limit myself to such specific structure except as hereinafter claimed.

I claim:—

1. The combination with a rope to cable splice in which the cable is laid as a core to the rope and is reduced in size intermediate the ends of the splice and the ends of the rope strands are reduced in order that the splice may taper at its upper end from its largest diameter to the diameter of the cable, of a sleeve surrounding and fitting the splice at the end of the cable, a second sleeve surrounding and fitting the splice at the point where the cable is reduced in size, said first and second sleeves being of a length preventing relative movement of the rope and cable at the end of the cable and at the point where the cable is reduced in size, and a third tapered sleeve surrounding and fitting the tapered end of the splice and coextensive therewith.
2. The combination with a rope to cable

splice in which the cable is laid as a core to the rope and is reduced in size intermediate the ends of the splice and the ends of the rope strands are reduced in order that the splice may taper at its upper end from its 30 largest diameter to the diameter of the cable, of a sleeve surrounding and fitting the splice at the end of the cable, a second sleeve surrounding and fitting the splice at the point where the cable is reduced in size, said 35 first and second sleeves being of a length preventing relative movement of the rope and cable at the end of the cable and at the point where the cable is reduced in size, a third tapered sleeve surrounding and fitting 40 the tapered end of the splice, and securing and coextensive therewith elements extended through each of said sleeves and into the strands of the rope, said securing elements being of such length that they do not enter 45 the cable.

In testimony whereof I hereunto affix my signature.

SAMUEL EVERETT CARNEY.
